United States Patent Office

Des. 197,213
Patented Dec. 31, 1963

197,213

DOOR HANDLE

John R. Morgan, Wheeling, Ill., assignor to Amerock Corporation, Rockford, Ill., a corporation of Illinois

Filed June 19, 1963, Ser. No. 75,433

Term of patent 14 years

(Cl. D10—8)

FIG. 2 is a top view of the door handle.

FIG. 3 is a front elevational view of the door handle.

FIG. 4 is a side elevational view as viewed from the right of FIG. 3 and showing the side opposite the side shown in FIG. 1.

FIG. 5 is an enlarged sectional view taken along the line 5—5 in FIG. 3.

I claim:

The ornamental design for a door handle, substantially as shown.
